UNITED STATES PATENT OFFICE.

CHARLES W. HARROLD, OF WARREN, OHIO, ASSIGNOR TO THE HARRIS AUTOMATIC PRESS COMPANY, OF NILES, OHIO, A CORPORATION OF OHIO.

PLATE-HOLDER FOR PRINTING-PRESSES.

1,168,498.

Specification of Letters Patent. Patented Jan. 18, 1916.

Application filed May 7, 1914. Serial No. 836,985.

To all whom it may concern:

Be it known that I, CHARLES W. HARROLD, of Warren, in the county of Trumbull and State of Ohio, have invented certain new and useful Improvements in Plate-Holders for Printing-Presses; and I do hereby declare the following to be a full, clear, and exact description of the invention, such as will enable others skilled in the art to which it appertains to make and use the same.

The primary object of this invention is to provide means for facilitating the attachment of plates to and their removal from the plate holders of printing-presses.

In the accompanying drawings, Figure 1 is an enlarged view of a portion of a printing-press cylinder showing my present improvement. Fig. 2 is a plan view of one of the clamping members.

Referring to the drawings, 1 designates a rod which is mounted in the plate-carrier, which latter in the present instance is shown as a cylinder 2, but my present improvement may be applied to any form of plate-carrier.

On rod 1 I mount the means for clamping the plate. In the drawings I have shown a single clamping member in each figure, but it will be understood that in actual practice a series of clamping members is employed.

3 designates an arm mounted on rod 1 and having a widened head 4 formed with an opening 5 extending longitudinally thereof, said opening being wedge-shape with its reduced end terminating at one side of the head. Preferably the inner wall 6 of the opening is inclined, or set at an angle to the outer straight wall 7.

Extending longitudinally through the wedge-shape opening is a binding element 8, which is shown in the form of a roll, which when moved toward the reduced end of the opening will bind the plate therein. This roll is preferably carried by a block 9 which is slideable transversely of the opening, which latter is grooved at its center, in its inclined wall 6, to accommodate such block. A

spring 10 acting on block 9 serves to normally hold roll 8 in its plate-binding position, that is, at the reduced end of the wedge-shape opening. The block 9 has a rod 12 extending therefrom and projecting through an opening in the head and beyond one face of the latter. Any suitable means may be

employed whereby this rod may be manipulated to overcome the tension of spring 10 and cause roll 8 to be moved out of clamping position. I have shown a pivoted plate or lever 13 for this purpose. A slight tap on the lever will release the bind of the roll on the plate. Each of the supporting arms 3 is provided with a screw 14 by means of which the arm as a whole may be moved to place the plate under tension.

In practice, the operator by manipulating lever 13 draws the roll 8 to the widened end of opening 5 to allow the printing plate α to be inserted between the roll and the straight wall 7 of the opening. Immediately upon releasing his hold on lever 13 the spring acting on the block will force the roll into the reduced portion of the opening and thus firmly bind the plate therein. After the plate has been thus secured to all the supporting arms the necessary tension may be applied to the plate by means of screws 14.

The advantages of my present invention will be readily appreciated. It will be seen that the attachment and removal of a plate may be easily effected in a very short time.

I claim as my invention:

1. A plate holder for printing-presses comprising a support having a wedge-shape opening, a sliding block movable transversely of said opening, a binding roll carried by said block, a spring serving to hold said block and roll at the reduced end of said opening, a rod extending from said block, and a lever engaging said rod for moving said block and roll as against the tension of said spring.

2. A plate holder for printing-presses comprising a support having a wedge-shape opening, a block movable transversely of said opening, and a wedging roll having a reduced portion mounted on said block, said roll and block being movable toward and away from the reduced portion of said opening.

In testimony whereof, I have signed this specification in the presence of two subscribing witnesses.

CHARLES W. HARROLD.
